GEORGE A. MATTERN, OF BERKELEY, CALIFORNIA

GIRDLED TRUNKS ADAPTED FOR SUN BATHING

Application filed June 16, 1930. Serial No. 461,290.

My invention relates in general to the class of wearing apparel, and in particular to garments which are intended to give to the wearer maximum freedom of action and body exposure, consistent with modesty and decency.

Body covering from primitive times, in accordance with temperature conditions and natural environment, has either grown up from or has been reduced to a breeches-cloth or clout, which in modern times among civilized people has assumed for special uses the form of what is known as trunks, and these have continually tended to become simpler and more abbreviated, subject to an equally continuous protest from those who insist upon modesty and decency. Bathing suits, for example, illustrate this tendency, though the protest is somewhat weakened by the fact that, presumptively at least, undue attention is negatived by supposedly protracted immersion. But the present vogue of sun-bathing has rendered the dictates of modesty and decency more imperative, especially since sun-bathing requires the maximum exposure of the body; and in this use the usual correctives afforded by additional members, such as coverings above and skirts below the waist, are subversive of the use intended. The consequence is that modesty and decency are, in practice thrown to the winds by the sun-bather donning trunks alone, of a brevity, pliancy and thickness (knitted goods usually) clearly objectionable.

It is the object of my invention to correct this by providing trunks which will not thus offend, but at the same time will be particularly adapted for sun-bathing both as to the maximum exposure afforded, and also with respect to an alternative diminution of such exposure whenever required for transient comfort. With this object in view, my invention comprises essentially a pair of trunks having a breech-covering girdle. This garment, together with its advantageous elaborations, will be hereinafter fully described, reference being had to the accompanying drawings, in which I have illustrated the garment in its preferred form, it being understood that changes may be made without de-

parting from the spirit of the invention as defined by the claims hereunto appended.

In the drawings:—

Fig. 1 is a front elevation of my girdled trunks, showing it in condition for normal wear in the sun's rays.

Fig. 2 is a section on the line 2—2 of Fig. 1, showing the double thickness of the garment due to the trunks and the embracing girdle.

Fig. 3 is a front elevation of the garment showing the girdle raised from its normal breech-covering position to a position adapting it to cover a portion of the wearer's body above the waist, when for temporary comfort he finds it expedient.

The complete garment comprises a pair of trunks 1 and a breech-covering girdle 2, united only at the waist line, where a gathering tape 3 in a hem 4 serves to support the garment. The trunks and girdle may be an integral unit or separate joined pieces. In its preferred form they are, as here shown, a single piece. Due to the waist-zone between the bulging body region above and the hips below, it will be seen that the girdle 2 conforms to and covers only the bulging breech zone of the trunks 1, when down in normal position, as in Fig. 1, and when raised, as in the hour-glass form of Fig. 3, it conforms to the bulge of the body region above the waist. Thus the girdle which in its literal definition is a close fitting and clinging member or band having the width of and enveloping only the breech of the trunks, is also and thereby adapted to fit and cling without extraneous support, to the wearer's body above the waist, a result fully insured by the nature of the material, of which in practise the garment is made, namely knitted goods, preferably knit in a direction providing for a circumferential phase of elasticity conducive to supporting fitness. The intention in the use of the garment, is to normally wear it as in Fig. 1, with the girdle enveloping closely and clinging to the breech region of the trunks. The double thickness due to trunks and the superimposed girdle gives to the garment, either wholly or substantially, a proper appearance responsive to the requirements of

modesty and decency. If, due to any temporary change in temperature, the wearer desires less exposure, he may turn away from the observation of others for a brief period and then flex the girdle upwardly, with the waist line as an axis, as in Fig. 3, until it fits and clings to his body above said line, in which alternative position it needs no further support for its incidental and brief use.

10 It should now be noted that this girdle member or band, as in Fig. 1, is not to be confounded in any sense with the skirt of a bathing suit, which term implies a rather free, flowing member of greater length than the parts it covers, nor, as in Fig. 3, is it to be compared to the body member of such suit. In its normal use it is a true girdle in the nature of a belt or band closely fitting and clinging to the trunks and necessarily of a width sufficient only to cover the breech portion of the trunks, while in its raised or alternative use it is self sustaining and covers only such limited portion of the body as its width permits. The term girdle, as used herein, must, therefore, be taken in this sense, and the garment as a whole be regarded as a new and useful article of manufacture.

I claim:—

30 1. The herein described garment comprising a pair of trunks provided with a girdle of substantially the width and normally embracing the breech region of the trunks, said girdle being adapted, by flexing in the waist line, to be turned from its normal position to an alternative position embracing the wearer's body above the waist line.

40 2. The herein described garment comprising a pair of trunks and a girdle joining the trunks in the waist line and otherwise free thereof, adapting it to be turned alternatively to and from embrasure of the trunks and of the wearer's body above the waist line, said girdle being of a width substantially equal to and fashioned to fit the breech region of the trunks.

50 3. The herein described garment comprising a single piece of goods fashioned to form a pair of trunks and a girdle, the two members merging in the waist line about which the girdle is adapted to be turned alternately to and from embrasure of the trunks and of the wearer's body above the waist line, said girdle being of a width substantially equal to and closely fitting the breech region of the trunks.

In testimony whereof I have signed my name to this specification.

GEORGE A. MATTERN.
